UNITED STATES PATENT OFFICE.

HARLAN MOORE, OF NEW YORK, N. Y.

BOTTLE OR JAR CLOSURE DEVICE.

1,300,222.

Specification of Letters Patent.

Patented Apr. 8, 1919.

Application filed May 22, 1917. Serial No. 170,180.

To all whom it may concern:

Be it known that I, HARLAN MOORE, a citizen of the United States, residing at New York, in the county of New York and State 5 of New York, have invented certain new and useful Improvements in Bottle or Jar Closure Devices, of which the following is a specification.

My invention relates to the class of closure 10 devices which consists simply of a disk of paper board or other flexible material of sufficient strength, flexibility and elasticity to be sprung or pressed into an internal annular seat or croze-like groove in the mouth 15 of the bottle or jar, and is especially adapted for use in connection with the commonly used form of milk bottles. The need for a simple, sanitary, cheap, and easily-applied closure device of a temporary nature in connection 20 with the business of supplying milk at retail in returnable and refillable bottles has brought this class of bottle closure in very extensive use, and it is conceded that in many of the larger cities of the United States 25 many thousands of these disk closures are used every day. It is also well known that these disk closures are defective in several respects, mainly in that they require a tool of some sort to remove them, and even with 30 a tool are frequently forced into the bottle as when the finger or thumb is employed, thereby splashing or spilling the contents of the bottle and injuring the disk sufficiently to destroy it as a closure device, and thereby 35 prevent its being inserted again by the consumer should only a portion of the contents be removed at a time. A further objection is that in removing the disks with a tool, the bottle is not only frequently chipped around 40 its mouth, but the disks are punctured and afterward not always sufficiently liquid-tight to permit the bottle to be shaken to mix the layer of cream that gathers in the neck of the bottle when the bottle has been 45 allowed to stand a few hours.

It is the object of my invention to overcome the objections just pointed out to the use of this class of bottle closures, and to this end it consists in providing a simple 50 thin flexible and elastic disk with a slit or cut extending from its interior to the circumference. This construction of disk enables me to quickly and slightly dish said disk by overlapping the sector-shaped sections of the disk adjacent to the edges formed 55 by the slit, and applying the closure so

dished to the bottle by inserting the dished disk in the inner annular seat or groove within the neck of the bottle. A bottle so constructed and arranged enables one to 60 easily and slightly lift with the finger nails or thumb, and without the use of a pointed tool, or instrument, the upper overlapping sector-shaped section of the disk to permit the air to get under the disk or cap and between the disk or cap and the contents of 65 the bottle, thereby destroying the partial vacuum, and enabling the closure to be easily and quickly lifted out of the neck of the bottle, when it is desired to use the contents of the bottle, without said closure being destroyed or marred for further use, or in any way disturbing the contents within the bottle. The above construction of bottle closure can be made with the minimum use of 70 paper, cost of cutting dies, mechanical or manual operations and cost of production. Other operations and advantages of my invention, and manner of applying and using 75 the same will appear from the hereinafter 80 detailed description.

The invention consists of structural characteristics of elements and relative arrangements thereof, which will be hereinfater more fully set forth, and particularly point- 85 ed out in the appended claims.

In the accompanying one sheet of drawings, similar reference characters indicate the same parts in the several figures in which:

Figure 1 is a vertical section on line 1—1 of Fig. 3 of a bottle neck with my improved disk closure applied.

Fig. 2 is a top plan view of the preferred form of the disk closure as cut from suitable 95 material and before being placed in the neck of the bottle.

Fig. 2' is a top plan view of a modified form of the disk closure.

Fig. 3 is a top plan view of the bottle 100 showing the disk closure shown in Fig. 2 in its applied position.

Fig. 4 is a side view of the disk shown in Fig. 2.

Fig. 5 is a side view of the disk having its 105 sector-shaped sections adjacent to the slit overlapped and in dished condition to be applied to the bottle.

Figs. 6, 7 and 8 are top plan views illustrating further modified structures embodying my invention, and

Fig. 9 is a top plan view of a further

modified form of disk when applied to a bottle having a croze-like groove in its mouth.

Referring to Figs. 1, 2, 2^a, 3, 4, and 5 of the drawings, 10 is an imperforate disk of 5 flexible and elastic material preferably of paper, but any other suitable material having the same general characteristics may be employed, if so desired. Said disk 10 is substantially circular, or elliptical in form 10 of slight eccentricity with a smooth periphery, and is provided with a slit or cut 11 extending from the center to the smooth circumference as shown in Fig. 2, or by a shorter slit 11^a from the circumference to a 15 point in the interior of the disk 10, as illustrated in Fig. 2^a.

Said disk 10, before being slit or cut as shown in Figs. 2 and 4, is preferably made 20 slightly larger in diameter than the internal diameter of the annular seat or groove within the neck of the bottle made to receive the disk or cap closure for reasons to be presently described.

Said disk 10 is made to assume the dished 25 construction as shown in Fig. 5 by drawing over one or both of the radial cut edges formed by the slit or cut 11 in opposite directions with the center of the disk 10, as a pivotal point, so as to form the upper and 30 lower overlapped sector-shaped sections 12 and 13, as indicated in Figs. 1, 3 and 5. The dished disk formed as described is inserted preferably with the convex side toward 35 the interior of the bottle 14 into the usual inner annular groove or seat 15 in the neck of the bottle 14, and when released the dished disk 10 naturally and freely expands, and forces its outer and smooth circumferential edge tightly and uninterrupt- 40 edly against the annular vertical wall of the seat or groove 14, as shown in Fig. 1, thus preventing any possible leakage of the contents of the bottle at this outer portion of the closure.

45 The overlapping sector-shaped sections 12 and 13, are forced against each other and hence prevent any of the contents of the bottle in passing between them and out of the bottle, and this bringing together of 50 said sections 12 and 13 is effected to a still higher degree owing to the dished shape of the disk 10, when the bottle 12 is turned with its bottom up, as the pressure of the 55 contents of the bottle will tend to force or flatten out the disk, and hence press the lower or inner shaped section 13 against the outer or upper section 12, and insure a fluid-tight joint between said overlapped sections 12 and 13, as will be readily understood. After 60 the slotted disk or closure 10 has been firmly locked or seated in the groove 15 within the neck of the bottle 14 as shown in Figs. 1 and 3, and it is desired to remove the disk or cap 10, and contents of the bottle 14, all 65 that is necessary is to slightly lift the ex-

posed edge of the upper sector-shaped section 12 with the thumb or finger nails, when the outside air will pass between the upper and lower sector-shaped sections 12 and 13 and destroy the partial vacuum under the 70 disk or cap 10, when on further pulling and lifting of said upper section 12, which is now easily accomplished, the diameter or circumference of the circular disk 10 is reduced to such an extent that the outer circular edge of the disk 10 is easily freed from the inner annular seat or groove 15 of the bottle, and the disk or cap 10 is readily lifted from the bottle without any undue strain on any of the parts of the disk or 80 cap 10, and without destroying its further use, should it be desired to replace it again as a closure for a bottle.

While I have shown and described the dished disk or cap 10 as applied to the bot- 85 tle with its convex side toward the inside of the bottle, I do not limit myself to this particular arrangement as the closure has been found to be satisfactory, when used with its convex side oppositely arranged 90 from that shown in Fig. 1, and toward the outer side of the bottle.

The modifications shown in Figs. 6, 7, 8 and 9, involve the same invention as de- 95 scribed with reference to Figs. 1 to 5 and are applied, used and operated in the same manner.

In Fig. 6, the slit instead of being radial is made in two distinct lines 16 and 17 forming a tab 18, while in Fig. 7, is shown a radial slit 19 having a semi-circular tab 20 formed thereon. Fig. 8 illustrates a radial slit 21 with a semi-circular cut-out sec- 100 tion 22.

Fig. 9 shows a disk or closure adapted to 105 be inserted in the mouth of a bottle 14' having an under cut or croze-like annular groove or seat 15' formed therein, and hence the circumferential or outer edge 23 of the upper sector-shaped section is required to 110 be cut away as shown in order to permit its entire under side to lie flat upon the upper side of the lower sector-shaped section.

From the foregoing disclosure of the construction and operation of my invention, it 115 will be readily seen that all the advantages and objects of my improved closure set up in the statement of invention and descrip- 120 tion are fully carried out, and all the dis- advantages of the present and usual forms of solid disk caps or closures which are ordi- 125 narily pushed down with the thumb into the neck of the bottle, resulting in the unsanitary thumb splashing and nauseating feeling to the customer, which are inevi- 130 table when the bottle is well-filled, are entirely overcome by the use of my construction of cap or closure and method of removing the same in which the air by the use of the fingers, is admitted at once under the cap

or closure, and without any of the fingers or thumb coming in contact with the contents of the bottle, or said contents unexpectedly spurting out of the neck of the 5 bottle.

Many other modifications will readily suggest themselves to any one without departing from the essential and broad elements of the herein described invention, as 10 for example, instead of the slit 11 of Fig. 2, or slit 11^a of Fig. 2^a, being radial as shown, said slits may be at any angle to a tangent at the circumference, and longer or shorter than those illustrated in Figs. 2 and 2^a, as 15 indicated for example by slit line 17 in Fig. 6.

What I claim is:

1. As an article of manufacture, a receptacle closure comprising an imperforate 20 readily yielding disk substantially circular in form having a smooth periphery and a continuous slit from its center to the circumference and adapted to have its sections adjacent to the slit overlap each other when 25 said disk is forced into and its periphery uninterruptedly seated against the inner side of the mouth of a receptacle, whereby after the closure has been placed in the mouth of a receptacle the top or outer 30 slitted edge of the overlapping sections is capable of being easily bent up or lifted to permit the air to enter into the receptacle and at the same time form a projecting tab with 35 which to remove said closure from the receptacle.

2. As an article of manufacture, a receptacle closure comprising an imperforate readily yielding dished disk having a 40 smooth periphery and integral overlapping separable sector-shaped sections when said disk is forced into and its periphery uninterruptedly seated against the inner side of the mouth of a receptacle, whereby after the closure has been placed in the mouth of a 45 receptacle the top or outer edge of the overlapping sections is capable of being easily bent up or lifted to permit the air to enter into the receptacle and at the same time form a projecting tab with which to 50 remove said closure from the receptacle.

3. As an article of manufacture, a receptacle closure comprising an imperforate readily yielding dished disk formed from a substantially circular flat body having a 55 smooth periphery and a continuous slit

from its circumference to a point within the disk removed from the circumference and adapted to have its sections adjacent to the slit overlap each other when said disk is forced into and its periphery uninterruptedly seated against the inner side of the mouth of a receptacle, whereby after the closure has been placed in the mouth of a receptacle the top or outer slitted edge of the overlapping sections is capable of being easily bent up or lifted to permit the air to enter into the receptacle and at the same time form a projecting tab with which to remove said closure from the receptacle. 60

4. The combination of a receptacle being 70 air tight except at one opening, a yielding disk slightly larger than the opening and having a smooth periphery inserted within said opening, said disk having a continuous slit from its center to the circumference and adapted to have its sections adjacent to the slit overlap each other when said disk is forced into and its periphery uninterruptedly seated against the inner sides of the 75 opening of the receptacle, whereby after the opening of the receptacle, the top or outer slitted edge of the overlapping sections is capable of being easily bent up or lifted to permit the air to enter into the receptacle and at 80 the same time form a projecting tab with which to remove said disk from the receptacle. 85

5. The combination of a receptacle being 90 air tight except at one opening, a yielding disk slightly larger than the opening and having a smooth periphery inserted within said opening, said disk having a continuous slit extending from a point at the circumference to a point within the disk and adapted to have its sections adjacent to the slit overlap each other when said disk is forced into and its periphery uninterruptedly seated against the inner sides of the 95 opening of the receptacle, whereby after the opening of the receptacle, the top or outer slitted edge of the overlapping sections is capable of being easily bent up or lifted to permit the air to enter into the receptacle and at 100 the same time form a projecting tab with which to remove said disk from the receptacle. 105

In testimony whereof I affix my signature.
HARLAN MOORE.
